UNITED STATES PATENT OFFICE.

BENNETT BOND, OF LESTERVILLE, MISSOURI.

SPRING MATTRESS.

Application filed February 6, 1922. Serial No. 534,237.

To all whom it may concern:

Be it known that I, BENNETT BOND, a citizen of the United States, and resident of the city of Lesterville, county of Reynolds, and 5 State of Missouri, have invented certain new and useful Improvements in Spring Mattresses, of which the following is a specification, containing a full, clear, and exact description, reference being had to the 10 accompanying drawings, forming a part hereof.

My invention relates to improvements in spring mattresses, and has for its primary object a mattress which is made adjustable 15 so that a single or three-quarter bed can be arranged to accommodate two people, either as a double bed or as twin beds.

A further object is to construct a spring mattress in two sections, which sections can 20 be moved apart and a hammock swung between, or a table may be placed between the two sections.

In the drawings—

Fig. 1 is a top plan view of my improved 25 mattress;

Fig. 2 is a fragmental plan of one side of one of the sections showing the manner of holding the supporting legs in position;

Fig. 3 is a cross section taken on the line 30 3—3 of Fig. 1; with the sections pulled apart and in place in a bed frame;

Fig. 4 is an enlarged fragmental section showing the manner of attaching the sections to the main frame;

Fig. 5 is a top plan view of the main 35 frame; and

Fig. 6 is a sectional view taken on the line 6—6 of Fig. 5.

In the construction of my device, I employ 40 a main frame having side rails 7. Adjacent the ends of these side rails are end rails 8. These end rails are provided with elongated slots 9, which extend entirely therethrough. Intermediate the ends rails 7 are rails 10, the upper surfaces of these rails being flush with the upper surface of the rails 8, while the rails 7 are at some distance below (see Fig. 3 and Fig. 6).

Mounted on the main frame 7 are sliding 50 sections having side rails 11 and 12 and end rails 13. These sections are also provided with a spring mattress 14, which is preferably of link construction and is attached to the end rails 13.

Secured to the rails 11 are pivoted legs 15 55 which are held in raised position by means

of spring clips 16. Extending through the rails 12 and through the slots 9 are bolts 17, which slidably secure the sections to the main frame.

When my device is intended to be used as a double bed the sections are pushed together, as illustrated in Fig. 1, and thus form practically a continuous spring for the bed. It will be noted in this instance, however, that the combined width of the sections is greater than that of the main frame, this extension or width varying according to the size of bed used. That is, if the device is used on a single bed, the sections 70 will extend further over the edges of the main frame than when used on a three-quarter size.

When it is desired to transform the bed into twin beds, the sections are moved apart, 75 as illustrated in Fig. 3, and the legs 15 lowered so as to rest on the floor. In this manner the rails 11 will be supported while the rails 12 are supported by the bars 10, thus removing all strain from the bolts 17 and 80 preventing any sagging of the sections.

It will also be noted from Fig. 3 that when the sections are pulled apart, the rails 12 do not cover the bars 10 entirely, but leave a projecting shoulder, and on this projecting shoulder either a hammock can be supported in which a small child can sleep, or a table can be supported between the twin beds.

It will be noted that the bars 7 project 90 on both ends of the main frame. This is for the purpose of preventing contact of the sections with the head and foot of the bed, as the bars 7 are made just long enough to fit in the bed.

My device can be used either in iron beds or in the old-fashioned wooden bed where slats are employed, for supporting the mattress, and in this event all the slats except 100 the slat at the head and the slat at the foot of the bed are removed, and the main frame rested on these two slats only.

My device is especially intended for hotel purposes, as by having a number of these devices on hand, a room containing only a 105 single bed can be quickly equipped with double or twin beds without the necessity of moving bedsteads from one room to another.

Having fully described my invention, 110 what I claim is:

A spring mattress comprising a main

spring having a pair of spaced apart parallel side rails, an end rail extending from side rail to side rail located adjacent the ends of said side rails, said end rails having
5 their upper faces above the upper faces of the side rails, and being provided with longitudinally extending and spaced apart slots formed vertically therethrough, parallel rails having their upper faces flush with the
10 upper faces of the end rails located between the side rails and secured to the end rails, a pair of rectangular sections located slidably to and from each other on said end

rails, said sections provided near their adjacent edges with fastening means extending through the slots in the end rails for adjustably securing the same thereto, the intermediate rails serving as a support for one edge of the rectangular sections when the same are in extended position, and folding legs for supporting the opposite edges of said sections when the same are in extended position.

In testimony whereof, I have signed my name to this specification.

BENNETT BOND.
